UNITED STATES PATENT OFFICE.

EDWIN NORTON, DECEASED, LATE OF PAGET WEST, BERMUDA, BY LUCY E. NORTON,
EXECUTRIX, OF NEW YORK, N. Y.

CAN-CAPPING MACHINE.

1,279,413.

Specification of Letters Patent. Patented Sept. 17, 1918.

Application filed March 16, 1916. Serial No. 84,633.

To all whom it may concern:

Be it known that EDWIN NORTON, deceased, late a citizen of the United States, residing at Paget West, Islands of Bermuda, invented new and useful Improvements in 5 Can-Capping Machines, of which the following is a specification.

This invention relates to improvements in can capping machines, and more particularly to that type in which the caps or heads are seamed to the can body within a vacuous chamber, one object of the present invention being to so construct the parts which inclose the cans within a vacuous chamber during 10 the seaming operation, that the length of movement of one part relatively to the other during the operation of inclosing a can to be seamed shall be reduced to a minimum.

A further object is to subdivide the can-inclosing structure and to effect the closing of said structure by a limited movement of one of said subdivisions relatively to the other.

A further object is to provide simple and 25 efficient interchangeable devices whereby the bells in which the cans to be sealed are disposed, may be adapted to receive and hold cans of various dimensions.

With these and other objects in view, the 30 invention consists in certain novel features of construction and combinations of parts as hereinafter set forth and pointed out in the claims.

In the accompanying drawings; Figure 1 35 is a view of a portion of a can capping machine showing the application of the improvements; Fig. 2 is an enlarged sectional view showing the arrangement of can holding devices in one of the lower bell members, 40 platforms for two different sizes of cans being shown; Fig. 3 is a plan view of the same, and Figs. 4, 5, 6, 7 and 8 are detail views.

1 represents suitable framework in which seaming mechanism 2 is mounted and suitable means are provided for actuating said seaming mechanism and for controlling its operation. The seaming mechanism 2 (which will be hereinafter referred to as the seaming head) is inclosed within a bell or receiver 3, mounted in the frame work. The wall of the bell or receiver 3 may be enlarged at its lower end and provided with

a groove to receive a packing ring 4 to engage and form an air-tight connection with the flanged upper end of a lower bell-member or receiver 5, in which a can to be sealed will be located, as hereinafter explained. The bells or receivers 3 and 5 are normally so disposed that the lower end of the upper bell will be in a plane, a short distance above 60 the plane of the upper end of the lower bell, so that a very short movement will suffice to bring the two bell-members together and form an air tight chamber in which the seaming of the cap to the can body will be 65 performed. Suitable means are provided (such for example, as illustrated in Patent No. 781,087 to Norton and Hodgson January 31, 1905) for bringing the two bell or sealing chamber members together and 70 means will also be provided for exhausting the sealing chamber during the seaming operation. These specific mechanisms do not constitute part of the present invention and need not be more particularly described 75 herein.

A plurality of lower bell or receiver members 5 will be provided and these are mounted upon rotary platform or turn-table 6. The turntable may be manually operated to 80 bring the lower bell or receiver members, successively, under the upper bell or receiver member for coöperation with the latter as previously explained, to form a closed sealing chamber, in which the can and its cap 85 are subjected to the action of the seaming head for seaming the cap to the can body. Means for operating the turntable, such as shown in the patent to Norton and Hodgson hereinbefore referred to, may be employed. 90

In order that the lower bell or receiver members shall be adapted to receive and properly hold cans of various sizes in position to be presented to the seaming head, without varying the length of movement of one bell or receiver member relatively to the other when the superimposed bell or receiver members are brought together, the devices now to be described are employed.

A platform 7 provided with a supporting spider or frame 8, is disposed within each lower bell member 5 and constitutes a support upon which a can to be sealed is mounted. This can support or pad is con-

structed to fit snugly within the lower bell or receiver member and is secured in place by means of a central bolt 9, the headed upper end of which passes through the platform 5 and the lower end is threaded to enter a threaded socket in the bottom of the bell member 5. A plurality of can supports will be provided and they may be used interchangeably for supporting cans of different 10 heights, and the platform portions of said supports may be made of different sizes to accommodate cans of various circumferential dimensions.

A centering ring 10 is removably mounted 15 within each bell 5 so as to closely hug the wall of the same above the can support and at its upper edge, this ring is somewhat enlarged to form a shoulder 11 which rests upon a shoulder 12 in the bell 5. The ring 10 is provided with several pairs (preferably four) of flanges 13 forming vertical grooves 14 for the reception of the outer edge portions of centering jaws 15 adapted at their inner edges to engage and center a can 16. 20 Each centering jaw may conveniently consist of a plate which enters a recess 17 in the frame of the can support adjacent to the platform portion 7 thereof. Each centering jaw or plate is connected with the ring 10 25 by means of screws 18, the threaded portions of which enter said jaws, while the heads 19 of said screws are loosely disposed within recesses 20 in the ring 10. Each centering jaw or plate is beveled at its inner, upper 30 corner as shown at 21, and an annular plate 22 secured to the upper edge of the centering ring 10, overlies the outer portions of the upper ends of the several centering jaws. Each centering jaw is provided in its outer 35 edge near the upper end thereof, with a socket 23, in which one end of a spring 24 is seated, the other end of said spring entering a socket in the centering ring and bearing against a threaded plug 25 closing the 40 outer end of said socket and by means of which the tension of said spring may be adjusted.

It will be understood, that centering rings and jaws of various heights will be provided, which may be employed interchangeably in the bell 5 to accommodate cans of different heights, and that centering jaws of different widths will be provided and adaptable for use, interchangeably, to accommodate cans of different circumferential dimensions.

When the several bells or receptacle members 5 on the turntable shall have been provided with the supporting, centering and holding device (according to the size of the cans to be sealed), said bell or receptacle members will be ready for the reception of the cans, with caps thereon. When a can 16 is being inserted into the bell, the base flange 65 27 of said can will engage the beveled upper

ends of the jaws or plates 15 and as the can descends, said jaws or plates will be pressed outwardly against the resistance of the springs 24 and when the bottom of the can shall have become seated on the can support, the springs 24 will have pressed the upper portions of the jaws against the upper portion of the can and thus the can will be accurately centered within the bell. When a can (with a cap thereon) shall have 70 been thus placed in the bell 5, the operator will move the turntable until the bell member 5 (having the can therein) becomes disposed directly under the upper bell or receptacle member 3, when the two bell or receptacle members will be caused (by any suitable means) to come together and form the tightly closed sealing chamber which may be exhausted of air and in which the operation of seaming the cap to the can will be 75 performed as hereinbefore stated. After the seaming operation shall have been completed, the bell or receptacle members will be separated, and the operator will move the turntable another step, thus permitting the 80 removal of the sealed can and presentation of another lower bell in position to accomplish the sealing of the can therein.

Slight changes might be made in the details of construction of the invention without departing from the spirit thereof or limiting its scope.

Having fully described the invention what is claimed as new and it is desired shall be covered by Letters-Patent, is:—

100

1. In a can capping machine, the combination of a sealing chamber, sealing mechanism within said chamber, said chamber comprising upper and lower separable bells, supporting and centering devices removably located within the lower bell, and means for moving said lower bell into and out of alignment with the upper bell.

2. In a can capping machine, the combination with a sealing chamber comprising upper and lower bells, one movable vertically relatively to the other, a can support in the lower bell, centering jaws in said lower bell above the can support therein, and a horizontally movable support for said lower bell whereby the same may be moved into and out of vertical alignment with the upper bell.

3. In a can capping machine, the combination with superimposed bells coöperative to form a sealing chamber, and sealing means in the upper bell, of a can support in the lower bell, a ring mounted in said lower bell above and independently of the can support therein, and yielding can centering jaws connected with said ring.

4. In a can capping machine, the combination with superimposed bells coöperating to form a sealing chamber, seaming means in the upper bell, a can support in the lower

bell, a ring in said lower bell above said can support; a plurality of can centering jaws, means loosely connecting said jaws with said ring, springs engaging said ring and the upper portions of said centering jaws, and means for moving said lower bell into and out of vertical alinement with the upper bell.

In testimony whereof, I, LUCY E. NORTON, have signed this specification, as executrix ¹⁰ of the estate of EDWIN NORTON, deceased, in the presence of two subscribing witnesses.

LUCY E. NORTON.
